UNITED STATES PATENT OFFICE.

PAUL JEANMAIRE, OF MÜLHAUSEN, GERMANY.

MERCERIZING APPARATUS.

SPECIFICATION forming part of Letters Patent No. 734,333, dated July 21, 1903.

Application filed May 12, 1900. Serial No. 16,464. (No model.)

To all whom it may concern:

Be it known that I, PAUL JEANMAIRE, residing at Mülhausen, Alsace, in the Empire of Germany, have invented certain new and useful Improvements in Mercerizing Apparatus, of which the following is a specification.

This invention relates to improvements in an apparatus for mercerizing textile fabrics; and the object of the invention is to provide means for stretching the fabric after the same has been impregnated with the mercerizing fluid, so that the fabric becomes of greater width than when it left the bath and a silk-like gloss is imparted to the goods, while the fabric remains of the same or approximately the same length.

For this purpose the invention consists in the combination, in a mercerizing apparatus, of a plurality of laterally-acting card-clothed extensor-rolls located to operate in succession upon the impregnated fabric; and the invention consists, further, in the combination with these rolls, arranged as stated, of setting-rolls and of means for washing the fabric.

In the accompanying drawings, Figure 1 is a diagram indicating the various rolls and vats of an apparatus embodying my invention. Fig. 2 is a diagram illustrating another form of apparatus embodying my invention, and Fig. 3 is a side view of one of the card-clothed extensor-rolls.

Referring to Fig. 1, *a* indicates the fabric, and *k k* the extensor-rolls, of which two are shown arranged so as to act in succession upon the impregnated fabric. Three rolls are employed in this construction, arranged, respectively, before the first extensor-roll, between the first and second, and after the second. These rolls are preferably provided with roughened surfaces—card-clothed, for instance—so that the fabric when upon the same cannot shrink, but retains its size. This causes the fabric to set to more or less extent, depending on the speed of the rolls, kind of fabric, nature of bath, &c. In other words, the fabric does not shrink after passing off one of these rolls, or if it shrinks at all then to a less degree than were it not passed in contact with the setting-roll. In order to render this setting action more effective by increasing the time of application to the setting-roll, these rolls are preferably made of

very much larger size than the extensor-rolls *k*, as shown. The extensor-rolls are provided with card-clothing, so as to firmly engage the fabric for the lateral stretching, the card-clothing being applied, for example, to the outer portions of the roll, as at *m*, and projecting above the intermediate portion of the roll, as clearly shown in Fig. 3. The fabric *a* passes into the impregnating-bath and is there impregnated—for example, with a solution of caustic soda at about 33° Baumé. From the bath it passes over the first setting-roll, beneath the first extensor-roll, over the second setting-roll, beneath the second extensor-roll, over the third setting-roll, and thence over rolls *g* in the sulfuric-acid bath *h*. Spray-pipes *d* are arranged below the second extensor-roll and spray the stretched fabric with water for washing the same simultaneously with the stretching action, the spray from the lower pipe *d* passing at one side of the upper pipe. This washing during the stretching action facilitates the stretching operation, causes a silk-like gloss upon the finished goods, and reduces the tendency to shrinkage, so that when the fabric leaves the last setting-roll it has very little, if any, tendency to shrink, and that is removed by the neutralization in the acid-bath *h* of any portions of the mercerizing fluid remaining in the goods. After passing the bath *h* the goods may be again washed and then dried or subjected to any other suitable well-known treatment.

In Fig. 2, *l* indicates a roll of fabric which has already been impregnated. *a* indicates the fabric upon and passing from this roll successively over the extensor-rolls *k k k*, which are in this case arranged in unbroken succession, each receiving the fabric directly from the preceding roll and stretching it to greater width, the fabric thereby undergoing three lateral stretchings. From the last extensor-roll *k* it passes upon the setting-roll *c*, upon which it is washed by spray-pipes *d d*, arranged in proximity to the roll. Thence it passes over the rolls *g* in the acid-bath for final neutralization. The goods may thereafter be subjected to any suitable finishing treatment. The successive extensor-rolls are each located so as to receive and act upon the fabric before the same has opportunity to

shrink or to shrink to any marked extent from the dimensions to which it was stretched by the preceding roll. By this means an intermittent stretching, each time to a greater width, is accomplished with a shorter or longer period of rest for the fabric between each stretching, according to whether the fabric is fed directly from one extensor-roll to the next, as shown in Fig. 2, or passes over intermediate setting-rolls, as in Fig. 1. By these intermittent stretchings, with a period of rest between each stretching, the width of the fabric may be increased from ten to fifteen per cent. in the case of cotton cloth. The surface of the setting-rolls may be smooth instead of card-clothed. In this case, however, they do not act as setting-rolls, but merely serve as conveying-rolls between the extensor-rolls, affording a surface for the cloth to pass over during the period between the intermittent stretchings.

I am aware that rollers of the card-clothing are well known, and, on the other hand, that they are as heretofore used of no utility for producing a very great enlargement of the fabric and have never been employed, therefore, but to maintain the fabric at its original dimensions and prevent the shrinkage of its form. That which I claim as my invention is the location of the card-clothing, not upon a roller, but upon a determined part of the surface of the bars of the usual spreading-roller. By these novel means I render the spreading-rollers capable of producing the effect of extension which is absolutely impossible to be obtained without the same. The placing of card-clothing upon rollers is common, but the adaptation of the cards to the spreading-rollers, as set forth, has never been accomplished with success before now.

Having thus described my invention, I claim as new and desire to secure by Letters Patent—

1. In a mercerizing apparatus, the combination of a mercerizing-bath, and a laterally-acting card-clothed extensor-roll, the card-clothing being located at the outer ends of the bars of said roll, and the portions of said bars between said outer ends being smooth, substantially as set forth.

2. In a mercerizing apparatus, the combination of a plurality of laterally-acting card-clothed extensor-rolls located to act in succession intermittently upon the impregnated fabric, the card-clothing being located at the outer ends of the bars of said rolls, and the portions of said bars between said outer ends being smooth, substantially as set forth.

3. In a mercerizing apparatus, the combination of a plurality of laterally-acting card-clothed extensor-rolls located to act in suc-

cession intermittently upon the impregnated fabric, the card-clothing being located at the outer ends of the bars of said rolls, and the portions of said bars between said outer ends being smooth, and means for washing the fabric simultaneously with the stretching of the same on the last roll, substantially as set forth. 65

4. In a mercerizing apparatus, the combination of a plurality of laterally-acting card-clothed extensor-rolls located to act in succession intermittently upon the impregnated fabric, the card-clothing being located at the outer ends of the bars of said rolls, and the portions of said bars between said outer ends being smooth, means for washing the fabric simultaneously with the stretching of the same on the last roll, and a setting-roll located to receive the fabric from the last extensor-roll, substantially as set forth. 70 75 80

5. In a mercerizing apparatus, the combination of a plurality of laterally-acting card-clothed extensor-rolls located to act in succession intermittently upon the impregnated fabric, the card-clothing being located at the outer ends of the bars of said rolls, and the portions of said bars between said outer ends being smooth, means for washing the fabric simultaneously with the stretching of the same on the last roll, a setting-roll located to receive the fabric from the last extensor-roll, and a setting-roll between said last extensor-roll and the preceding roll, substantially as set forth. 85 90 95

6. In a mercerizing apparatus, the combination of a mercerizing-bath, a setting-roll, an extensor-roll located between said bath and setting-roll, said extensor-roll being provided at the outer ends of its bars with card-clothing, and the portions of said bars between said outer ends being smooth, the outer ends being smooth, and means between said extensor-roll and setting-roll for washing the fabric, substantially as set forth. 100

7. In a mercerizing apparatus, the combination of a mercerizing-bath, a setting-roll, a plurality of extensor-rolls located between said bath and setting-roll, said extensor-rolls being provided at the outer ends of their bars with card-clothing, and the portions of said bars between said outer ends being smooth, each extensor-roll adapted to receive the fabric in wider condition than the preceding roll, and means for directing a washing liquid upon the stretched fabric passing over said rolls, substantially as set forth. 105 110 115

In testimony that I claim the foregoing as my invention I have signed my name in presence of two subscribing witnesses.

PAUL JEANMAIRE.
